(57) **CLAIM**

The ornamental design for the integrated touch screen display, as shown and described.

DESCRIPTION

FIG. 1 is an isometric view of an embodiment of an integrated touch screen display showing our new design.

FIG. 2 is a front elevational view of the embodiment.

FIG. 3 is a rear elevational view of the embodiment.

FIG. 4 is a right-side elevational view of the embodiment.

FIG. 5 is a left-side elevational view of the embodiment.

FIG. 6 is a top plan view of the embodiment; and,

FIG. 7 is a bottom plan view of the embodiment.

Any broken lines and/or patterns in the drawing are for illustrative purposes only and form no part of the claimed design.
